UNITED STATES PATENT OFFICE.

WALTER A. SCOTT, OF MINNEAPOLIS, MINNESOTA.

SOUND DEADENER.

Application filed May 24, 1926. Serial No. 111,470.

The main object of the invention is to provide a cheap but highly efficient sound deadening structure which may be applied to any use where it is desired to absorb and prevent sound, such as in walls, heavy machinery, car wheels, typewriters, sound screens, etc.

A further object is to provide a sound deadening structure including a filling or wall of small nonresonant particles, adapted to disintegrate sound vibrations and contacting each other in the least possible manner, whereby the transmission of sound will be minimized.

In most forms of sound deadening material and insulation the wall or filling, although capable of disintegrating sound vibrations to a considerable extent, will transmit a considerable amount of sound due to the fact that the filling elements contact each other extensively or that the material is pressed or rolled into a relatively compact sheet.

I provide a sound deadening wall formed from a plurality of loosely packed, relatively nonresonant spherical particles which cause the sound vibrations to be broken and which contact each other only at one point, that is, their point of tangency. Where irregular or cubical particles are used as a filler the several particles touch each other along considerable areas of their surfaces and thus transmit a considerable amount of sound.

An additional object of this invention is to provide a sound deadening structure especially adapted for revoluble members, such as gears and wheels.

These and other objects of the invention will be apparent from the following description made in connection with the accompanying drawings, wherein like characters refer to similar parts throughout the several views, and in which—

Fig. 1 is a cross section of a sound deadening wall made in accordance with my invention;

Fig. 2 is a side elevation of a car wheel having my invention embodied therein,

Fig. 3 is an end view taken on Fig. 2 with some portions broken away and others shown in section, and

Fig. 4 is a detail view on a greatly enlarged scale showing one of the minute elements.

In Fig. 1 of the drawings, a pair of vertical partitions 5 and 6 are illustrated spaced

some distance apart. The right hand partition 6 is shown as having its lower end turned up to form a bottom 6^a, between the edge of which and the lower end of partition 5 I provide a packing strip 7 of nonresonant material. The space between partitions 5 and 6 is filled with a multiplicity of minute spherical particles preferably constructed of nonresonant material. While a great variety of material may be used, lead shot, such as employed in shot gun shells or small carbon spheres have been found highly efficient. Walls 5 and 6 may be secured together in spaced relation in any suitable manner, and are here shown as secured by a transversely disposed nutted bolt 8.

Figs. 2 and 3 illustrate a noiseless type of car wheel constructed in accordance with my invention. The wheel proper 9 is constructed in the usual manner having a relatively heavy hub 10 and the flanged tread portion 11. In many types of car wheels, such as are employed on railway and street cars depressed portions or annular recesses are formed in the wheel about the hub and extending adjacent the tread portion. If the wheel is not provided with annular recesses, as described the same may be easily machined therein on both sides of the wheel and preferably narrow annular shoulders 12 are left at the edges of the recess, the purpose of which will be readily seen. These recesses are filled with a relatively thin layer of small nonresonant spherical particles X on the outer sides of which annular plates 13 are clamped. Annular packing strips are disposed between the shoulders 12 and the adjacent edges of the plates to minimize the transmission of sound. The plates may be clamped to wheel 9 in any suitable manner, and are here shown as secured by means of a plurality of transversely disposed nutted bolts 15, passing through plates 13 and through the wheel proper.

It is, of course, a well known fact that sound vibrations will be greatly disintegrated and prevented in passing, or attempting to pass through a wall formed of nonresonant particles. If these particles are uniform in size and shape, the efficiency of the device will be greater, since the spaces between the particles are apt to be more regular and smaller.

However, where the particles contact each other considerably, the wall so formed, even though constructed of comparatively non-

resonant material will transmit a considerable amount of sound vibrations.

In providing a wall formed of minute spherical particles of nonresonant material,

5 I minimize the property of that wall for transmitting sound, since each particle can touch an adjacent particle at only one point, and since moreover, the particles will be packed in very close arrangement thereby 10 being operative to more thoroughly disintegrate the sound vibrations. No binding material is used between the particles.

My structure, therefore both minimizes the transmission of sound through the wall 15 and gives a maximum disintegration of the vibrations in traveling therethrough.

While the spherical particles may be formed of various other nonresonant material, fine gun shot has been found to have 20 the highest degree of efficiency. Lead of course is a comparatively nonresonant material, may be cheaply obtained and easily melted to form the spherical particles. Moreover, in heavy machinery and wheels, 25 where often it is desired not to lessen the weight of the parts, a thin layer of this material may be used to accomplish the purposes desired.

It will, of course, be understood that various changes may be made in the form, de- 30

tails, proportions and arrangement of parts, and that my sound deadening structure is capable of application to any use where it is desired to eliminate or minimize sound vibrations, without departing from the scope 35 of this invention.

What is claimed is:

1. A sound absorbing wall comprising a multiplicity of substantially spherical un- 40 united particles of non-resonant material and means to retain said particles in contacting relation.

2. A sound absorbing construction includ- 45 ing a multiplicity of symmetrical members of non-resonant material arranged over a substantial portion of the surface of a sound emitting body.

3. A sound absorbing construction includ- 50 ing a multiplicity of ununited spherical members of non-resonant material arranged over a substantial portion of the surface of a sound emitting body.

4. A sound absorbing construction includ- 55 ing a multiplicity of ununited spherical members of non-resonant material arranged on both sides and covering a substantial portion of said sides of a sound emitting body.

In testimony whereof I affix my signature.

WALTER A. SCOTT.
